UNITED STATES PATENT OFFICE.

ANNIE H. BEST, OF BROOKLYN, NEW YORK, ASSIGNOR OF ONE-HALF TO WILLIAM M. BEST, OF BROOKLYN, NEW YORK.

MECHANICAL ATOMIZER.

1,146,394.

Specification of Letters Patent. Patented July 13, 1915.

Application filed June 11, 1913. Serial No. 773,114

To all whom it may concern:

Be it known that I, ANNIE H. BEST, a citizen of the United States, and resident of Brooklyn, in the county of Kings and State of New York, have invented certain new and useful Improvements in Mechanical Atomizers, of which the following is a specification.

My invention relates to certain improvements in mechanical atomizers for liquid fuels.

My invention particularly involves a novel and highly efficient atomizer through which the liquid fuel is delivered under pressure and from which it escapes in the form of a finely sub-divided mist or spray.

My improved atomizer is adapted for use in connection with various types of furnaces for melting metals, heating articles of metal, or other material or for heating boilers and in its different embodiments it is adapted for delivering fluid in either a flat, fan-shaped spray or in a substantially conical one.

Reference is to be had to the accompanying drawings in which similar characters of reference indicate corresponding parts throughout the several views; and in which—

Figure 1 is a sectional elevation through one form of my improved atomizer; Fig. 2 is a top plan view thereof; Fig. 3 is a face view of the atomizer nozzle with convex spray guiding plates; Fig. 4 is a view similar to Fig. 3, but showing concave plates; Fig. 5 is a view similar to Fig. 3 but showing straight edged plates; and Fig. 6 is an end view of the inner member of the nozzle.

My improved atomizer nozzle, is of the general type in which there is employed a body portion having an outlet opening and an inner member so formed as to give the fluid a whirling movement as the latter approaches the outlet.

In the specific form illustrated particularly in Fig. 1, I employ a body portion or casing member 10 and a spindle or inner member 11 therein. The body has a removable cap 12 through which the outlet delivery opening 13 extends and the spindle has a head 14 for whirling the fluid. This spindle head 14, which constitutes an important portion of my invention, is of an exterior diameter substantially equal to the internal diameter of the body 10 while the main por-

tion of the spindle in the rear of the head is of considerably smaller diameter so that the fluid may readily flow lengthwise of the atomizer body to the spindle head. The head is substantially cylindrical and terminates in a substantially hemispherical portion adapted to project into a substantially hemispherical cavity in the inner surface of the atomizer cap or head 12. The spindle head is provided with a relatively large number of helically disposed grooves or passages resembling screw threads, each groove or passage extending not only around the cylindrical portion of the head but also extending around and inwardly upon the hemispherical portion, so as to all terminate at substantially the same point at the extreme end of the head in the axis of the latter. Thus all of the grooves or passages at the point where they meet are extending substantially transversely of the terminal curved face of the head. In other words, the grooves start as helical grooves and terminate substantially as spiral ones. The number of these grooves may be varied but I have found that six is a very satisfactory number. As previously stated the atomizer head 11 has a concave or substantially hemispherical recess in its inner surface opposed to the end of the nozzle head 13 and the outlet 13 is in alignment with the axis of the spindle and opposite the point to which the grooves or passages converge. The end of the wall of the cap or head 12 is comparatively thin and may be flat across the outer end and the outlet 13 is preferably countersunk so that the peripheral wall defining the outlet is narrow and in some forms for sprays of wide angle is merely a knife edge. The fluid in traveling through the passages 15 increases its speed of travel as it approaches the outlet and the several streams flowing in the several passages converge directly at the outlet opening 13. The streams are all traveling in different directions and each in a substantially tangential direction, so that at the instant that they unite they tend to break each other up and unite to form a finely sub-divided spray of conical shape the flare or angle of the cone being dependent to a certain extent upon the thickness of the wall at the outlet and the angle of the countersink.

The spindle head may be substantially flat at the extreme outer portion and will

of course be substantially flat over a limited area if the spindle head be hemispherical. Preferably the spindle head carries a small relatively sharp conical projection on its end surface and in alignment with its axis. This projection at its base is slightly smaller than the outlet opening so as not to interfere with the free escape of the fluid, but at the same time to tend to guide the several streams through the outlet from the ends of the grooves. The main object of this conical projection or point is to prevent the outlet from getting clogged or to clear it should it become clogged. The spindle may be moved back and forth so as to project the point 16 through the outlet and clear the latter of any obstruction. It normally projects a short distance during the use of the device. The outlet may vary somewhat in size for the same nozzle as shown in Figs. 3, 4 and 5 for different fuels or different delivery pressure.

One important feature of my nozzle is its adaptability for use in forming a substantially flat, fan-shaped spray when such is desired in preference to the conical spray. The outer end wall of the cap 12 is so constructed as to support two spray guiding or deflecting plates 17, 17 which present opposed surfaces forming a slot through which the spray from the outlet 13 escapes. Preferably the end surface of the cap 12 is substantially flat and each guiding or deflecting member 17 has a base flange 18, secured to said face in any suitable manner, as for instance by screws 19 extending through slots in said flange. By making the slots parallel to each other and at right angles to the general direction of the length of the member the two members may be adjusted toward and from each other so as to control the thickness of the body of the spray. These plates or guiding members need not extend parallel and preferably are curved toward each other at their ends as shown in Fig. 3 so as to secure the desired thickness and uniformity of density of the spray across its width, or I may employ members 17^a as shown in Fig. 4, which curve away from each other at their ends so as to increase the depth or thickness of the spray at its edges or I may employ guiding or deflecting members 17^b having substantially parallel edges as shown in Fig. 5. To prevent the accumulation of any liquid on the edges and to prevent it from flowing along the edges said edges are preferably notched or serrated as shown in Figs. 1, 3 and 4, although with some kinds of fuel or in some constructions the edges may be smooth as shown in Fig. 5. As previously stated the guiding or deflecting members may be omitted or removed when a conical shaped spray is desired.

Any suitable means may be provided for supporting the spindle at its rear end and

permitting of the removal or longitudinal adjustment thereof. As shown the rear end of the body 10 carries a removable sleeve 19 held in place by a threaded collar 20 screwing on to the body and binding a flange of 70 said sleeve against the end of the body. By unscrewing this collar 20 the spindle and sleeve may be removed from the body without effecting the relative adjustment of the sleeve and spindle. The spindle is screw 75 threaded within the sleeve and the sleeve at its outer end carries a suitable packing gland for preventing the escape of fluid past the threads. As the sleeve is normally held against longitudinal movement a rotation of 80 the spindle will effect an adjustment of the spindle head in respect to the outlet opening 13. The cap 12 may be rotated to get the desired relative positioning of the parts if desired instead of rotating the spindle. 85

Intermediate of the ends of the atomizer body 10 is a boss 22 to which a supply conduit 23 may be connected and this conduit closely adjacent to the nozzle carries a suitable valve 24 for shutting off the supply to 90 the nozzle. The body also preferably has cast integral therewith a lug 25 provided with a transverse opening 26 adapted to facilitate locking of the nozzle in the desired position in respect to the furnace. Adjacent 95 to the supporting lug 25 and the supply conduit 23 is preferably an annular flange 27 which may fit and close the opening to the combustion chamber through which the nozzle is inserted. 100

It is of course evident that my improved atomizing nozzle may be used in connection with various types of heating furnaces as well as steam boilers and it is also evident that various changes within the scope of the 105 appended claims may be made in the construction of the nozzle itself without departing from the spirit of my invention.

Having thus described my invention, what I claim as new and desire to protect by Letters-Patent, is:

1. A liquid fuel atomizer burner including a body portion having a smooth-surfaced, substantially cylindrical bore terminating in a smooth-surfaced, substantially hemispherical chamber with an outlet at the center of the latter, the peripheral wall around said outlet presenting a substantial knife edge, an inner member having a head including a cylindrical portion substantially fitting said 115 cylindrical bore and a substantially hemispherical portion adapted to fit within said hemispherical chamber and presenting a comparatively small pointed projection normally extending through said outlet, said cylindrical portion having a series of helical 120 grooves and said hemispherical portion having a series of helico-spiral grooves terminating adjacent to the base of said projection. 125

2. A liquid fuel atomizing burner includ- 130

ing a casing or body having a fluid-delivery passage terminating in an outlet, an adjustable member within said passage for causing the liquid to swirl as it emerges from said outlet, the outer end surface of said casing being substantially flat in a plane at right angles to the axis of said passage and two members secured to said surface upon opposite sides of said outlet and each including a flange extending outwardly from said surface and adjustable toward and from each other to give the emerging spray a substantially flat fan-shaped form.

3. A liquid fuel atomizing burner including a casing or body having a fluid-delivery passage terminating in an outlet, an adjustable member within said passage for causing the liquid to swirl as it emerges from said outlet, the outer end surface of said casing

being substantially flat in a plane at right 20 angles to the axis of said passage and two members secured to said surface upon opposite sides of said outlet and each including a flange extending outwardly from said surface and adjustable toward and from each 25 other to give the emerging spray a substantially flat fan-shaped form, said members being adjustable toward and from said outlet along said surface and each presenting a notched outer edge.

Signed at New York city, in the county of New York and State of New York this fifth day of June A. D. 1913.

ANNIE H. BEST.
